UNITED STATES PATENT OFFICE.

EDWARD WELLS, OF NEW HAVEN, CONNECTICUT, ASSIGNOR TO WELLS,
CRUTTENDEN & CO., OF SAME PLACE.

DESIGN FOR CARRIAGE-DOOR HANDLE.

Specification forming part of Design No. 5,163, dated August 1, 1871.

To all whom it may concern:

Be it known that I, EDWARD WELLS, of New Haven, in the county of New Haven and State of Connecticut, have invented a new Design for Carriage-Door Handles; and I do hereby declare the following, when taken in connection with the accompanying drawing and the letters of reference marked thereon, to be a full, clear, and exact description of the same, and which said drawing constitutes part of this specification, and represents in—

Figure 1 a front view, and in Fig. 2 an edge view.

This invention relates to a design for the handle of carriage-doors by means of which the latch is turned; and consists in the peculiar configuration, as shown in the accompanying drawing.

A square head, A, is fixed to the end of the spindle, and to the lower edge of this a horizontal bar, B, extends to the right and left the length of the handle, then, turning down at right angles, the two arms C are joined at their lower ends by the handle D, the said arms being ornamented by plain rabbets or shoulders, as shown in the drawing.

I claim as my invention—

The design for carriage-door handle, as herein described and shown in the accompanying drawing.

EDWARD WELLS.
